INVENTOR

Robert R. Page,

BY

Harold S. Penney ATTORNEY

UNITED STATES PATENT OFFICE.

ROBERT E. PAGE, OF NEW YORK, N. Y.

STRING PEG.

Application filed March 19, 1924. Serial No. 700,271.

My present invention relates to an improved form of string-peg for musical stringed instruments.

One important feature of my device is that the necessary force amplification to tension and tune a string is derived by the use of only one direct rotative reduction through means of a driven crown gear and a driver pinion in mesh therewith.

Another important advantage is, that through the above noted arrangement, the rotative direction of the string peg is the same as the rotative direction of the key or winding-stem, notwithstanding the simplicity and use of the two-gear reduction.

Another advantage of my construction is that owing to the arrangement of the casing and the crown gear speed reducing elements, the tension reaction of the tuned string upon the string-peg proper is prevented from cramping the device.

Another novel feature relates to means whereby the driving pinion is frictionally adjustably held for preventing reverse movement of the driven gear, or crown gear, due to strain of the tuned string on the string peg.

In the drawings Fig. 1 is a section elevation of my device taken on the line 1—1 Fig. 2,

Fig. 2 is side elevation of Fig. 1.

Fig. 3 is a plan view of the casing, showing the pinion gear.

Fig. 4 is side elevation of the string peg and crown gear.

Fig. 5 is an end view of the peg showing the gear.

Fig. 6 is a plan view of the casing cap.

Fig. 7 is side elevation of the key pinion.

Fig. 8 is a plan of the boss or washer.

Fig. 9 is a detail of the lock washer.

Fig. 10 is a detail of the locking screw.

Fig. 11 shows another form of pinion and gear tooth.

My device comprises, preferably, in a metal construction, a casing denoted by 1, which is substantially cylindrical, and provided with two screw fastening lugs 3 and 4, Fig. 3, whereby the complete device may be attached to a keyboard head, generally denoted by 5, Fig. 2.

The casing 1, has a circular interior which is finished in a smooth manner so as to receive therein and rotatively support a driven gear element 6 of substantially cylindrical construction, said gear 6 having its lower

open edge 7, Fig. 4 cut so as to develop a series of gear teeth 8 thereon, somewhat in the fashion of a so-called crown-cut gear. By arranging this gear in this preferred cylindrical form, I provide a long side-bearing surface B, which, coacting with the comparatively deep inside surfaces 9 of the casing interior 10, provides, in conjunction with the stem bore 11 in the casing cap 12, a 60 rotative mounting or bearing, which under the tension reaction or leverage of the string 22, Fig. 2 prevents cramping action of the above described parts and provides a long-faced easy bearing for smooth precise tuning rotation of all the coacting rotating parts.

To further the simplicity of the device and to facilitate rapid assembly of the device and effecting a saving in labor, I have 75 provided a cap 12, in the form of an apertured disc, the aperture 11 of which receives and rotatably supports the string-stem or peg 13, which is integrally and axially mounted upon the driven gear 6. The outer 80 diameter of the cap 12 is of such size as to permit it to be a force-fit into the upper part of the interior 10 of the casing 1, so that when the gear elements are assembled within said casing, they are enclosed there- 70 in finally by capping the casing 1, about as shown in Fig. 1.

The casing 1 is provided on its lower integral cover portion 14, with an apertured bearing disk 15, and which rotatably supports therein a stemmed driving or key pinion 16 in operative driving relation with the driven gear 6, as shown in Fig. 1. The driving pinion 16 is of smaller pitch diameter than the driven gear 6, and, as shown, 90 meshes with said gear 6 within the pitch circle thereof, so that rotation of the driving pinion 16 causes the driven gear 6 to rotate in the same direction, thereby permitting the player to tune his instrument in the 100 accustomed manner.

As a means for preventing rotation of the peg 13 due to the strain thereon of the tuned string, but which permits easy manipulation of the peg by the player, I have provided 105 means which, in cooperation with the pinion stem 17 and the finger key piece 18, sets up a variable opposing friction to the string-tension forces upon the driven gear 6 through its string peg 13. To this end the 110 pinion stem 17 for a portion of its length is made cylindrical and for the remainder of

its length is squared, as at 23, Figs. 1 and 7. The finger piece 18 has a collar or bead 24 and has a square recess or chamber 25 adapted to receive the squared portion 23 of the pinion stem for moving the stem, this recess extending through the body of the finger key. The finger key 18 has a bore 26 which communicates with the recess 25 and is in alignment with the threaded bore 27 in the square end of the finger stem. The bore 26 receives the finger key screw 20, the threaded end of which engages in said bore 27. The washer 15 is located on the cylindrical portion of the pinion stem 17 and bears against the outer side of the cover portion 14, and the split spring 19 is arranged around the cylindrical portion of the pinion stem between the washer 15 and the bead 24. It is thus seen that by inward movement of the screw 20 tension will be applied to the gear pinion 16 whereby it is frictionally held on the interior of the cover 14, and that this tension may be varied or adjusted by inward or outward movement of the screw 20, this tensioning of the gear pinion serving to prevent rotation thereof due to strain of the string on the peg 13. It will also be seen that the amount of force required to turn the peg 13 for tuning up the string is exactly the same as that required for letting down or loosening the string, and that this arrangement permits of steady turning of the peg 13 in either direction and provides for very perfect tuning of the string. The tension on the gear pinion 16 may be adjusted by the player or may be adjusted in manufacture and set.

In Fig. 11, I have disclosed a modified form of gearing. In this modification I have substituted a bevel pinion and gear, as a substitute for the internal type shown in Figs. 1 and 2, but in every other respect the details of construction of the modified form are like the preferred construction. In the modified form, it will be noted that the driven pinion retains the long cylindrical bearing face B, whereby to steady the string peg and to prevent cramping of the gears when under string tension.

Having thus described my invention, it should be understood that there may be modifications thereof and variations therein without departing from the spirit of the invention or exceeding the scope of the appended claims.

What I claim is:

1. In a sound instrument, a support having an extended smooth friction face; a gear thereon provided with a string stem and an extended smooth friction surface engaging said face; a pinion meshing with said gear and provided with a projecting driving stem; and a finger key on said driving stem.

2. In combination, in a sound instrument, a casing having a smooth inner cylindrical

face; a disk like member provided with a string stem and a smooth cylindrical peripheral surface snugly fitting in the casing and frictionally engaging said face.

3. In a sound instrument, a support having an extended face; a member provided with a stem and an extended face several times the diameter of the stem and frictionally engaging said face; and a finger key operatively connected to said member.

4. In a sound instrument, a casing having an inner cylindrical face; a gear provided with a stem and a cylindrical peripheral surface several times the diameter of the stem snugly fitting in the casing and frictionally engaging said face; a pinion meshing with said gear and provided with a driving projecting stem; and a finger key on said driving stem.

5. In a sound instrument, a support having a cylindrical face; a member provided with a stem and a cylindrical surface several times the diameter of the stem snugly fitting against and frictionally engaging said face; and a finger key operatively connected with said member.

6. In a sound instrument, a casing having a cylindrical wall; a gear therein provided with a stem and a bearing surface engaging said wall; a cap firmly secured in said casing and having a bearing aperture receiving said stem; a pinion meshing with said gear and provided with a projecting driving stem; and a finger key on said driving stem.

7. In a sound instrument, a substantially cylindrical casing; an exteriorly cylindrical interiorly toothed gear received in said casing with a friction fit and provided with a projecting stem adapted to secure a sounding string; a casing cap tightly fitting in said casing and having a stem bore receiving the stem, said cap and the casing co-operating to prevent binding by action of the string of the stem; a pinion meshing with said gear and provided with a projecting driving stem; and a finger key on said driving stem.

8. In a sound instrument, a substantially cylindrical casing having an outer wall portion; an exteriorly cylindrical interiorly toothed gear received in said casing with a friction fit and provided with a projecting stem; a bearing disk on the bottom surface of said portion; a pinion meshing with said gear and provided with a driving stem projecting through said disk; and a finger key on said driving stem.

9. In a sound instrument, a casing having a cylindrical wall; a crown gear having a friction fit with the wall and provided with a stem; a pinion within the casing and meshing with said gear and provided with a projecting driving stem; and a finger key on said driving stem.

10. In a sound instrument, a cylindrical casing having an outer wall portion; an exteriorly substantially cylindrical deep crown-cut driven gear rotatively conformably received in said casing with a snug friction fit against the cylindrical wall of the casing and provided with a projecting string stem, the teeth of said gear being directed in a direction opposite to that of the stem, the deep exterior face of the gear and casing co-operating to prevent binding by action of the string of the stem; and a pinion meshing with said gear and provided with a driving stem projecting through said wall portion. 5
11. In a sound instrument, a casing; a gear snugly received therein provided with a stem; a pinion meshing with said gear and disposed within the boundaries of the gear and provided with a projecting driving stem; and a finger key on said driving stem. 20
12. In a sound instrument, a casing having a cover portion having an eccentric opening; a string stem projecting from the casing; a driving stem projecting through said opening and connected to the string stem the latter having one terminal thereof snugly engaging the casing; a bearing disk mounted on said cover portion and provided with a bearing aperture registering with said eccentric opening; a driving stem connected with said string pin and provided with an intermediate cylindrical portion projecting through said bearing aperture having a squared outer end provided with a threaded axial bore; a finger key fitted on said outer end and having a recess alined with said threaded bore; a split ring around said driving pin between the key and said disk; and a screw adjustably received in said threaded bore whereby said spring may be tensioned. 35
13. In a sound instrument, a key board head having a string stem hole therein free of countersinks, a substantially cylindrical casing secured to said head exterior to the back face thereof; and having a substantially closed outer cover wall portion; a gear having a frictional fit with said casing provided with a stem projecting through said hole; an adjustable pinion meshing with said gear and provided with a driving stem having a finger key on said driving stem. 45
14. In a sound instrument, a key board head having a string stem hole therein; a substantially cylindrical casing disposed axially vertically on the back of said head and having a substantially closed outer cover wall portion and an outwardly laterally projecting flange at the inner edge engaging flat against the main back face of said head and formed with apertured projecting lugs; screws passing through said lugs and into the head; a crown gear adapted to frictionally fit with said casing provided with a stem projecting through said hole; a pinion meshing with said gear and provided with a driving stem projecting through said wall cover; and a finger key on said driving stem. 55
15. A peg for a sounding instrument comprising a casing, a crown gear frictionally disposed therein and being provided with an integral string stem, and an adjustable pinion arranged within the crown gear and finger key operatively associated with the pinion. 60
16. A peg for a sounding instrument comprising a casing with oppositely disposed perforated ears adapted to be suitably secured to the instrument, a crown gear snugly but rotatively disposed with the interior walls of the casing and an adjustable pinion within the crown gear and having key means extending therefrom and projecting thru the bottom wall of the casing. 65
17. A peg for a sounding instrument, a casing, a crown gear having an integral string stem, a pinion meshing with the crown gear and within the latter and being provided with a driving stem, off set from the string stem. 70
18. A peg embodying a casing having a crown gear, with a string stem, a pinion within the gear having a driving stem out of alignment with the string stem. 75
